UNITED STATES PATENT OFFICE.

CHESTER M. ANGELL, OF CHICAGO, ILLINOIS, ASSIGNOR TO VESTA BATTERY CORPORATION, OF CHICAGO, ILLINOIS, A CORPORATION OF ILLINOIS.

DESIGN FOR A STORAGE-BATTERY CONTAINER OR SIMILAR ARTICLE.

Application filed June 23, 1923. Serial No. 6,559. Term of patent 14 years.

To all whom it may concern:

Be it known that I, CHESTER M. ANGELL, a citizen of the United States, and residing in the city of Chicago, county of Cook, and State of Illinois, have invented a new, original, and ornamental Design for a Storage-Battery Container or Similar Article, of which the following is the specification, reference being had to the accompanying drawings, forming a part thereof.

On the drawings:

The figure is a perspective view of a storage battery container illustrating the design embodying my invention.

I claim:

The ornamental design for a storage battery container or similar article, as shown.

CHESTER M. ANGELL.
